QUILL CHUTE

Augusta M. Pressley, Concord, N. C.

Application March 11, 1937, Serial No. 130,397

1 Claim. (Cl. 139—241)

This invention relates to new and useful improvements in adjuncts for looms and more particularly to a quill or empty bobbin chute.

The principal object of the present invention is to provide a chute which will extend well in toward the lay of the loom so that empty bobbins or quills cannot fall into the loom mechanism and cause disruption of the operation of the machine and destruction of the quills.

10 Another important object of the invention is to provide a chute of the character stated which is of simple construction not susceptible to ready development of defects.

These and various other important objects and 15 advantages of the invention will become apparent to the reader of the following specification.

In the drawings:—

Figure 1 represents a side elevational view of the chute mounted in relation to a loom parts of 20 which are shown in section.

Figure 2 represents a bottom plan view of the chute.

Figure 3 is a perspective view of the chute.

Figure 4 is a fragmentary enlarged detailed 25 sectional view on the line 4—4 of Figure 2.

Figure 5 is an enlarged fragmentary detailed sectional view on the line 5—5 of Figure 1.

Referring to the drawings wherein like numerals designate like parts, it can be seen in Figure 1, that numeral 5 generally refers to a loom of conventional construction and involving the usual lay 6. Numeral 7 denotes the usual picker stick guideway through which the quills 8 drop when they become exhausted of thread.

35 These quills frequently do not fall directly into the receptacle intended for them but in various manners catch in the construction of the loom and frequently cause serious damage.

The present invention which is generally referred to by numeral 9 consists of the plate 10 40 of elongated shape having the upstanding end walls 11—12, the end wall 11 being in the shape of a large inclinedly disposed ear, while the end wall 12 is merely in the form of a quadrant 45 of a circle.

From the edge portion of the plate 10 adjacent the lay 6 a lip or extension 13 is provided which extends across the picker stick guideway so that as the quills 8 drop they must strike against this lip 13 and then are compelled to slide down the chute plate 10 into a receptacle suitably placed thereunder.

To the bottom side of the plate 10 is secured by rivets 14 or the like the ears 15—16 through which

the shaft 17 extends. Said shaft 17 is provided with a depending arm 18 at one end suitably secured to the shaft rigidly as at 19. This arm 15 is provided with a longitudinally extending slot 20 therein for receiving the bolt 21, the head of which is snugly seated in the pocket 22 of the plate 23, which plate 23 is provided with the guide flanges 24—24 slidably receiving the arm 18. The bolt 21 is provided with a nut 25 and the plate 23 is secured by bolts 26—26 to the frame *a* of 10 the loom 5, all as is clearly shown in Figure 1.

A second arm 27 is provided with a bearing 28 for receiving the remaining end of the shaft 17, the opposite end of this arm 27 being provided with the loop 29 through which a bolt 30 is disposed for securing this arm to the frame of the loom shown in Figure 1.

The bearing 15 as shown in Figure 2 is provided with a laterally extending lug 31 with which the stop lug 32 on the collar 33 is engageable to limit the swing of the chute 10. This collar 33 is secured to the shaft 17 by a set screw or the like 34.

For tensionally retaining the chute with its lip 13 toward the lay 6, a spring 35 is employed, one end of which is engaged into a recess in the bearing 15 as at 36 while its opposite end is engaged with the collar 37, which is fixed on the shaft 17 by a set screw 38.

While the foregoing specification sets forth the invention in specific terms, it is to be understood that numerous changes in the shape, size and materials may be resorted to without departing from the spirit and scope of the invention as claimed hereinafter.

Having described the invention, what is claimed 35 as new is:—

A quill chute for looms wherein a lay is employed; a chute structure having a bottom, and a lip extending from the bottom toward the lay, a rockable support for the chute, including a shaft 40 positioned horizontally along the bottom, supports at each end of the shaft for securing the shaft to the loom, a bearing for the shaft fixed to the bottom, a collar adjustable longitudinally on the shaft, a coil spring mounted on the shaft 45 and having its end secured respectively to said bearing and said collar for yieldably urging the chute in a position with the lip against the lay, said bearing having a stop on one end and a stop fixed to the shaft in the path of said first 50 named stop to limit swinging movement of the chute.

AUGUSTA M. PRESSLEY.
